LAPPING APPARATUS

David A. Wallace, Detroit, Mich., assignor to
Chrysler Corporation, Highland Park, Mich., a
corporation of Delaware

Application October 7, 1937, Serial No. 167,804

3 Claims. (Cl. 51—119)

This invention relates to an improved lapping apparatus.

More particularly, the invention pertains to an improved apparatus for lapping end surfaces such as the crowned ends of tappets and similar articles of the type commonly used in internal combustion engines and compressors.

One of the main objects of the invention is the provision of lapping apparatus of this character by which such relative movements between a lapping element and the surface operated upon are produced that the possibility of retracing of scratch lines in the surface is guarded against.

Another object of the invention is the provision of apparatus of this kind which is adapted to bring a lapping element into conformity with successively adjacent portions of crowned surfaces of different curvatures.

A further object of the invention is the provision of an improved driving connection between a lapping element of a tool and its driving member which accommodate self-adjustment of the operative surface of the lapping element to crown surfaces of different pieces of work.

Still further objects of the invention are to provide a lapping machine by which a plurality of pieces of work can be simultaneously lapped for a predetermined period of time; to provide a machine of this type which automatically predetermined the lapping period and which, at the end of the lapping period on one piece of work, discontinues the drive of that piece and moves the lapping tool which has been operating thereon, into an unobstructing position to facilitate convenient loading and unloading of the work while a plurality of other pieces of work are being lapped.

An illustrative embodiment of the invention is shown in the accompanying drawings, in which:

Fig. 1 is a top plan view, partly in section, and showing portions removed to disclose the underlying structure, of a machine embodying the invention.

Fig. 2 is a transverse vertical sectional view taken on the line 2—2 of Fig. 1.

Fig. 3 is a fragmentary vertical sectional view taken on the line 3—3 of Fig. 2.

Fig. 4 is a fragmentary radial sectional view taken on the line 4—4 of Fig. 1.

Fig. 5 is a fragmentary vertical sectional view taken on the line 5—5 of Fig. 2.

Fig. 6 is a fragmentary horizontal sectional view taken on the line 6—6 of Fig. 5.

Fig. 7 is an end elevational view of the structure

shown in Fig. 5 and taken as illustrated by the line 7—7 of the latter figure.

Fig. 8 is a fragmentary vertical sectional view taken on the line 8—8 of Fig. 2.

In the form of the invention shown in the drawings, the lapping apparatus includes a stationary base structure, generally designated by the numeral 10, having a central, vertically upwardly extending hub part 11 in which a hollow spindle 12 is rotatably supported by rolling contact members 13 and 14. Non-rotatably fixed to the spindle 12 is a work supporting carriage 15 of circular shape having a central opening 16 through which the spindle 12 extends. The top portion of the work supporting carriage 15 is detachably secured to a radial flange 17 extending outwardly from the spindle 12 by cap screws 18. Provided on the work supporting carriage 15 are a plurality of arcuately spaced work-holding members, generally designated by the numeral 19 in Figs. 2 and 20. Each work-holding member includes a sleeve 20 seated in an opening 21 in the carriage 15 and detachably secured to the latter by cap screws 22. Provided in the interior of each sleeve 20 is a pair of rolling contact bearings 23 in which a tubular spindle 24 is rotatably supported. The tubular spindle 24 has an open upper end portion for receiving the stem part 25 of a tappet 26. A plug member 27 extending into the lower end portion of the tubular spindle 24 has an upper 30 extremity so formed as to provide a seat for the lower end portion of the tappet stem 25. A pulley wheel 28 is mounted on the exterior of the tubular spindle 24 and non-rotatably secured to the latter by a key 29. Belts 30 extend around the circumferentially arranged and arcuately spaced series of work-holding members 19 and are engaged in the belt grooves of the pulleys 28 thereof. The belts 30 also extend around a driving pulley 31 which is radially spaced outwardly 40 from the series of work-holding members in order to bring the belts out of contact with at least the pulleys of one of the work-holding devices 19, as illustrated in Fig. 1. During rotation of the work supporting carriage 15, as hereinafter more 45 clearly set forth, each successive work-holding device is moved into radial alignment with the driving pulley 31 in order to bring the pulley of each successive work-holding member out of operative engagement with the belts 30.

The work supporting carriage 15 has a downwardly extending lower structure on which is provided a worm gear ring 32 that is meshed with a worm 33 by which the work supporting carriage 15 is drivingly rotated about the axis of the 55

spindle 12. The drive pulley 31 of the work holding devices 19 and the worm 33 by which the work and tool carriages are rotated are driven from a common source including a pulley 100 mounted on a shaft 101 which is journalled in housing 102. The pulley 100 may be driven by a motor (not shown) or other suitable means and its shaft 101 is provided with pinions 103 and 104 which transmit the drive to gears 105 and 106, respectively. The gear 105 is operatively connected with the worm 33 by belt and pulley apparatus, generally designated at 107, and the gear 106 is operatively connected by belt and pulley mechanism 108 and a shaft 109 with a gear unit 110, shown in Fig. 3, by which the drive pulley 31 is operated. The gear unit 110 includes a housing 111 in which one end of the shaft 109 is journalled. A shaft 112 having an axis disposed substantially normal to the shaft 109 is journalled in the housing 111 and drivingly connected therewith by bevel gears 113. The drive pulley 31 is non-rotatably fixed to an external end portion of the shaft 112.

The rotatable work supporting carriage 15 is provided with a lubricant discharge system which comprises discharge pipes 34 having their outlet end portions located in close proximity to the end portions of the tappets 26 which are to be lapped. The pipes 34 communicate with passages 35 in the wall structure of the spindle 12 which leads from a lubricant well 36 formed in the stationary base structure of the machine. The lubricant well 36 is supplied with lubricant through a system of pipes, generally designated by the numeral 37. An upwardly extending circular flange 38 is provided on the rotatable work supporting carriage 15 for preventing outward throwing of lubricant. The lubricant discharged from the pipes 34 upon the work is allowed to run down into an annular trough 39 formed in the carriage 15 from which it is discharged into a well 40 provided in the stationary base structure 10. The well 40 has an outlet pipe 41 communicating therewith for returning lubricants to the base structure from which it was supplied through the system of pipes 37.

Provided on the upper end portion of the spindle 12 is a reduced end section 42 on which is non-rotatably mounted a lapping tool carriage, generally designated by the numeral 43, and comprising a central sleeve 44 on which radially extending arms 45 are detachably secured by cap screws 46. Each radially extending arm 45 has a vertically extending channel-way 47 formed in its outer extremity in which a lapping tool, generally designated by the numeral 48, is slidably mounted. Each lapping tool 48 comprises a base structure 49 having flanges 50 slidably engaged in the channel-ways 47 of the arms 45 and an electric motor 51, or other suitable driving mechanism, having a shaft 52 on the lower end of which is mounted a disc 53. The driven shafts 52 of each lapping tool are disposed above and associated with one of the work-holding members 19, respectively. The rotative axis of the driving shaft 52 may be concentric with the axis of rotation of the work supported by the hollow spindles 24, but, for reasons hereinafter set forth, in the lapping of certain types of crowned surfaces, it is preferable to have the axis of rotation of the shaft 52 arranged in eccentric relationship with respect to the axis of rotation of the work.

A disc 54 having an inverted cup-shaped lapping element 55 preferably comprising lapping

stone material is disposed below the disc 53 and axially and universally movably connected therewith by circumferentially spaced cap screws 56 which extend through oversize apertures 57 in the disc 53 and which are threaded in counterbored apertures 58 in the disc 54. A coil spring 59 seated in the counterbore of the aperture 58 bears between the discs 53 and 54 so as to yieldably urge the latter disc axially of the shaft 52 and to yieldably resist lateral movement of the disc 54 with respect to the disc 53. A drive pin 60 mounted on the disc 53 is received in an oversize aperture 61 provided in the disc 54 for transmitting the drive from the shaft 52 to the disc 54 and lapping elements 55 carried thereby. The lapping element 55 is preferably detachably mounted on the disc 54 by a screw 62 and located on the disc 54 in eccentric relationship with respect to the axis of rotation of the shaft 52.

In the form of the invention illustrated, electrical power is supplied to the motors 51 of the lapping tool 48 by conductors 63 which extend through a tube 64 mounted on the base structure 10 of the machine and extending through a passage 65 in the spindle 12. Each of the conductors 63 is electrically connected to a slip ring 66 mounted on the exterior of the tube 64 and confined in a housing 67 carried by and adapted to rotate with the spindle 12. The slip rings 66 remain stationary during rotation of the housing 67. Disposed in the housing 67 is a horizontal plate 68 on which posts 69 are mounted. Each post 69 is provided with a brush 70 which bears against one of the slip rings 66. The brushes 70 rotate in unison with the casing 67 and spindle 12 and they establish electrical connection between the slip rings 66 and bus bar rings 71 disposed in the housing 67, as illustrated in Fig. 2. Each electrical motor 51 of the respective lapping tools 48 is provided with conductors 72 which are respectively electrically connected with the bus bars 71.

The lapping tools 48 normally assume their lowermost positions, as illustrated at the left in Fig. 2, by virtue of their weight. As each lapping tool and its associated tool holding member 19, reaches the position indicated by the numeral 73 in Fig. 1, at which the driving connection between the belt 30 and the work-holding member is interrupted, the lapping tool is lifted to facilitate convenient removal of the tappet 26 after the latter has been lapped, and replacement of a tappet to be lapped in the work holder. This is accomplished by providing a lever 74 which is pivotally mounted on each of the arms 45 of the tool carriage and arranged so that its outermost end engages the lower extremity of the base portion 49 of each lapping tool 51, respectively. During rotation of the work and tool carriages 15 and 45, respectively, each of the tools 48 are successively lifted to accommodate removal of the work 26 and replacement of work in the work-holding members 19. This is accomplished by the provision of cam followers, generally designated by the numeral 75, which comprise rods 76 slidably mounted in tubes 77 mounted in circumferentially arranged apertures 78 in the central portion of the work supporting carriage 15. One cam following device 75 is provided for operating the lever 74 of each respective lapping tool 48. The upper end portion of each cam follower rod 76 is provided with a roller 79 which bears against a lever 74. Mounted on the other end of the cam follower rod 76 are rollers 80 which run upon a cam track 81 75

mounted on the upper extremity of the hub portion 11 of the base structure 10. The cam track 81 is provided with an upwardly extending projection 82 which lifts the cam follower associated with each respective lapping tool to rotate the lever 74 thereof and lift the tool as the latter is moved into the loading and unloading position designated by the numeral 73 in Fig. 1.

During operation of the foregoing apparatus, 10 a plurality of tappets or other articles are simultaneously lapped for a predetermined period of time, as determined by the time required to produce one complete rotation of the work carriage 15 from the loading and unloading station 73. During this lapping period, the lapping element 55 is revolved while the work is rotated. In the 20 illustration shown in Fig. 4, the lapping element 55 has an outer diameter slightly less than the diameter of the crowned surface of the tappet being operated upon. Relative movements 25 accommodated between the discs 54 which supports the lapping element 55 and the discs 53 of the driven shafts 52 permits the working surface of the lapping element 55 to become accommodated to the curvature of successively adjacent portions of the crown surface of the tappet. In this manner all portions of the crown surface of the tappet are subjected to uniform action of the lapping element 55, which by reason of its revolving movement accompanied by the rotational 30 movement of the work does not tend to retrace any of the scratch lines produced by the work by localized harsh particles of lapping material.

Although but one specific embodiment of the 35 invention is herein shown and described, it will be apparent that various changes in the size, shape and arrangement of parts may be made without departing from the spirit of my invention.

40. What I claim is:

1. Lapping apparatus comprising a work support, a spindle on said work support for drivingly rotating a piece of work and retaining a surface of the latter which is disposed transversely of its axis of rotation in position to receive a lapping operation, a lapping tool adjacent said support including a rotative driving member having an extremity in opposed spaced relationship with respect to said surface, means for supporting 45 said driving member for rotation about an axis substantially parallel to but laterally spaced from the axis of said spindle, a lapping device between said surface and said extremity of said driving member having a lapping surface engageable with said surface of said work and extending on respectively opposite sides of the axis of rotation of the latter throughout the entire course of relative movement of said work and lapping surface, means drivingly connecting said 50 member and lapping device including connecting elements having loose fitting engagement with one thereof for accommodating movement of said lapping device axially and transversely of

said driving member and so constructed and arranged as to retain said lapping device in eccentric relationship with respect to the rotative axis of said driving member and resilient members bearing between said driving member and said lapping device for yieldably urging the latter against said surface of said work.

2. Apparatus for lapping a crowned extremity of a tappet comprising a support, a spindle on said support for drivingly rotating said tappet and retaining said crowned extremity thereof in position to receive a lapping operation, a rotatable driving member adjacent said spindle having an axis parallel to the axis of the latter but spaced laterally therefrom and having an end portion disposed in spaced opposed relationship with respect to said tappet extremity, a lapping element axially slidably and transversely movably mounted on said extremity of said driving member in eccentric relation with respect to its axis and having a ring shaped abrading surface provided with a central opening extending on respectively opposite sides of the rotative axis of said work throughout all portions of the course of relative movement of the latter and said abrading surface engageable with the crowned surface of said tappet, and resilient means for yieldably urging said lapping element toward said tappet and adapted to accommodate movement of said lapping element to conform with the crowned extremity of said tappet during operation of said apparatus.

3. Apparatus for simultaneously lapping the ends of a plurality of tappets including a base structure, a rotatable carriage on said base structure having a plurality of arcuately spaced rotatable members thereon each adapted to support a tappet with its end surface exposed to receive a lapping operation, a tool carriage rotatably mounted on said base structure in axially spaced 40 substantially concentric relationship with respect to the axis of said work carriage, a plurality of lapping tools each comprising a rotative driving member having a lapping element axially and laterally yieldably mounted thereon in eccentric relationship with respect to its rotative axis, each tool being so mounted on said tool carriage as to accommodate movement of its respective lapping element toward and away from an end surface of one of said tappets respectively, means for simultaneously drivingly rotating each of said carriages, apparatus for simultaneously driving a plurality of said rotatable tappet support members, said apparatus being so constructed and arranged as to discontinue the drive of each of said members while they occupy a predetermined position in their course of movement by said work carriage, and means for moving each tool away from said work carriage as it reaches said position in order to facilitate removal of a lapped tappet from its support member and loading of a tappet to be lapped thereon.

DAVID A. WALLACE.
